[57]

ABSTRACT

A process is disclosed for dinitrating 4-branched alkyl-chlorobenzenes predominantly in the 2- and 6-positions with a mixture of concentrated sulfuric and nitric acids as the nitrating agent. A subsequent step of amination yields 4-branched alkyl-2,6-dinitroanilines which are useful as herbicides and plant growth regulants.

10 Claims, No Drawings

NITRATION PROCESS

This application is a continuation-in-part of U.S. Ser. No. 300,063, filed on Oct. 24, 1972, now abandoned.

This invention relates to a process of nitration.

More particularly this invention relates to the nitration of 4-branched alkyl-2,6-dinitrochlorobenzenes.

Still, more particularly, this invention relates to an improved process for preparing herbicidally active and plant growth regulant mono-N-substituted-4-branched alkyl-2,6-dinitroanilines, such as those described in U.S. Pat. Nos. 3,111,403; 3,257,190; 3,332,769 and 3,672,866, and more specifically the compound 4-tert-butyl-N-sec-butyl-2,6-dinitroaniline.

The 4-branched alkyl-2,6 dinitroaniline compounds prepared by the method of this invention are represented by the formula:

(I)

wherein R is selected from the group consisting of branched chain hydrocarbons containing from 3 to 7 carbon atoms, such as iso-propyl, iso-, sec- and tert-butyl, iso-pentyl, etc.; and wherein R₁ is selected from the group consisting of lower alkyl, cyclo-lower alkyl,

30
35

chain other than straight chain. As used herein, with respect to R₁, the term alkyl denotes both straight and branched chain hydrocarbons containing 1 to 6 carbon atoms such as methyl, ethyl, propyl, isopropyl, n-butyl, sec-butyl, t-butyl, n-amyl, sec-amyl, hexyl, etc.; alkyl groups of 3 to 60 carbon atoms are preferred, more preferable are the branched 3 and 4-carbon groups i-propyl, sec-butyl and t-butyl; the term cycloalkyl denotes monocyclic saturated hydrocarbons having 3 to 6 carbon atoms; such as cyclopropyl, cyclopentyl, cyclohexyl; the term cyclo-lower alkyl lower alkyl denotes groups such as cyclopropyl methyl, cyclo-hexylmethyl, etc. The term lower alkenyl denotes straight or branched chain hydrocarbons having 3 to 4 carbon atoms and at least one double bond such as allyl, 2-but enyl, 3-but enyl, pentyl, hexenyl and the like; the term lower alkynyl denotes straight or branched chain hydrocarbons having 3 to 4 carbon atoms and at least one triple bond such as propynyl, 2-butynyl, 3-butynyl, pentynyl and the like; the term lower-alkoxy-lower-alkyl denotes a $\text{CH}_3(\text{CH}_2)_m-\text{O}-(\text{CH}_2)_n$ group wherein m is 0 or 1 and n is an integer from 1 to 6, such as methoxymethyl, methoxyethyl, methoxypropyl, methoxyisopropyl, ethoxymethyl, ethoxyethyl, ethoxypropyl, ethoxyisopropyl, etc; the term di-lower-alkoxy-lower-alkyl denotes a $(\text{CH}_3(\text{CH}_2)_m-\text{O})_2-\text{C}_n-\text{H}_{2m+2n-2}$ group wherein m and n have the same meaning as above such as dimethoxymethyl, dimethoxyethyl, dimethoxypropyl, dimethoxyisopropyl, diethoxymethyl, diethoxyethyl, diethoxypropyl, diethoxyisopropyl, etc.

It is known to prepare, for example, the 4-tert-butyl-2,6 dinitroaniline compounds of this invention according to the following reaction sequence:

cyclo-lower alkyl lower alkyl, lower alkenyl, lower alkynyl, lower-alkoxy-lower-alkyl and di-lower-alkoxy-lower-alkyl.

As used herein, the term branched chain hydrocarbon denotes any configuration of the hydrocarbon

65 However, this method of preparing the 4-tert-butyl compounds suffers from two major drawbacks which prevent it from being an economically feasible method of producing the compounds. First, during the initial step of nitrating the para-t-butylphenol, the conditions

of high acidity necessary to carry out this step produce a considerable loss of the tertiary butyl group from the para- or 4-position. Even carrying out this reaction at reduced temperatures does not wholly overcome the consequent loss of yield. Second, the step of converting the 4-tert-butyl-2,6-dinitrophenol to the corresponding chloro compound of Formula III requires the uneconomical use of a chlorinating agent such as thionyl chloride and a complexing agent such as dimethyl formamide.

The process of this invention thus provides an economical method of preparing 4-branched alkyl-2,6-dinitrochlorobenzenes, which are intermediates in the preparation of 4-branched alkyl-2,6-dinitroanilines. This process possesses distinct advantages over any other method known to the prior art for producing these compounds.

According to the process of this invention, a 4-branched alkyl-chlorobenzene is reacted with a mixture of concentrated nitric and sulfuric acids at elevated temperatures to yield 4-branched alkyl-2,6-dinitrochlorobenzene.

For example, 4-tert-butylchlorobenzene is reacted with a mixture of concentrated nitric acid and sulfuric acids at elevated temperatures to yield 4-tert-butyl-2,6-dinitro chlorobenzene:

The preferred starting material is a 4-branched alkyl-chlorobenzene. With other halobenzenes such as bromo- or iodobenzene, the Br⁻ or I⁻ substituent is too susceptible to replacement at high temperatures. With respect to fluorobenzenes, it is considered that these are not economically feasible starting materials.

Many nitrating agents and nitrating systems involving their use are known, and sizeable textbooks have been written on the subject. Usually, a nitrating system must be specifically devised to meet the requirements of the compound being nitrated, and few generalizations regarding nitrating systems and the results of their use are, therefore, possible.

For example, in the text, *Nitration and Aromatic Reactivity* by Hoggett, et al. (Cambridge University Press 1971), the following isomer proportions for the mono-nitration of p-chloro-toluene were reported:

Thus the mono-nitration is about equally divided between the ortho position and the meta position, with respect to the alkyl substituent.

Further, it is known that alkyl substituents on a benzene ring tend to orient further ring additions, either ortho or para, to the alkyl substituent. Thus, Boocock and Hickinbottom (Journal of the Chemical Society, pp. 2587-9, 1961) report that the nitration of 4-tert-butylchlorobenzene produced predominantly 4-chloro-2-nitro-1-tert-butyl-benzene, i.e. mono-nitration ortho to the tert butyl group. Thus only a single nitro group was added in the ortho position to the tert-butyl group.

The method of this invention surprisingly produces dinitration in both meta positions to the branched alkyl group i.e. tert-butyl.

Still further, nitrating 4-chloroalkylbenzene is described by Nikolenko, et al. (Zhurnal Obshchei Khimii, Vol. 34, No. 12, pp. 4032-7, 1964). While a mixture of nitric and sulfuric acids is employed, the method produces only mono-nitration of the 4-butylchlorobenzene, and achieves only a 70-80% yield.

Still further, the text "Methoden Der Organischen Chemie", Houben-Wehl, Vierte Auflage, Band X/1 - Stickstoff - Verbindungen I, pp 553 to 581, in particular Table 39, describes the dinitration of a 4-branched alkyl-chlorobenzene i.e. 4-chloro-1-[2-methyl-butyl-(2)] benzene, with a large excess of fuming nitric acid (vis a vis - concentrated sulfuric acid and concentrated nitric acid of this invention) to produce a compound

which has a nitro substituent in the ortho position and the meta position with respect to the chlorine substituent. It is well known in the art that the mere changing of acids used for nitrating will not change the orientation of substitution of the nitro substituents on the benzene ring. Yet by utilizing the acids (and reaction conditions) of the nitration method of this invention, an unexpected nitration of the two ortho positions (2,6 positions) with respect to the chlorine substituent is obtained in high yields.

Thus, the nitration process of this invention achieves surprising results in producing a 4-branched alkyl-2,6-dinitro chlorobenzene in a one step process and in accomplishing substitution of the nitro groups almost exclusively in the two ortho positions with respect to the chlorine substituent.

The results achieved by this nitration process are also surprising in that, contrary to what would be expected, the conditions of elevated temperature and high acidity prevailing during the nitration process do not cause loss of the tertiary butyl group from the 4-position of the 4-tert-butylchloro-benzene.

The method of this invention employs as a nitrating agent concentrated nitric acid together with concentrated sulfuric acid. The concentrated nitric acid should be greater than 70% concentration by weight and preferably 90% by weight. However, good results have been achieved using 80% concentrated nitric acid and red fuming nitric acid at a concentration of nearly 100%. The concentrated sulfuric acid is preferably

98% concentration by weight with a specific gravity of 1.84, although fuming sulfuric acid may also be employed.

The use of the more concentrated nitric acid represents a departure from the conventional use of 70% nitric acid as a nitrating agent. Moreover, the use of the stronger nitric acid is a significant departure in view of the fact that, contrary to expectation and unlike nitration of the corresponding *t*-butylphenol, the stronger acid does not produce any significant loss of the tertiary butyl group from the 4-position. The materially higher yield of the desired 2,6-dinitro-*t*-butylchlorobenzene obtainable with 90% nitric acid, as compared with 70% nitric acid, employed under the same set of nitrating conditions, is shown in the following Table I.

15

TABLE I

t-butyl-chloro-benzene (moles)	HNO ₃ (Conc. by Wt.)	HNO ₃ (moles)	H ₂ SO ₄ (moles)	T (°C.)	t (hrs.)	Wt. Crude Prod. (g)	Crude Yield (%)
.10	90%	.60	.80	100	1	23	89
.10	70%	.60	.80	100	1	21.9	85
2,6-Dinitro- <i>t</i> -butyl- chloro- benzene	Mononitro- <i>t</i> -butyl- chloro- benzene		Pure 2,6-Dinitro- <i>t</i> -butyl- chloro- benzene				
(%)	(%)	Un- knowns (%)	(%)		M. P.		
95	0	5	85		91-101		
72	24	4	61		Gummy		

As the data contained in the above Table illustrates, use of the 70% nitric acid produces a substantial proportion of the mononitro-*t*-butylchlorobenzene, with a consequent unacceptably low yield of the dinitro-form.

Without intending that the scope of this invention be limited thereby, it is theorized that the concentrated sulfuric acid component of the nitrating agent employed in the method of this invention reacts with the nitric acid component to greatly increase the concentration of nitronium ions, which are the immediate reactants responsible for nitration. Nitric acid alone yields nitronium ions in accordance with the following equation:

However, the addition of sufficient sulfuric acid will yield the same nitronium ion concentration from only one-half of the original molar amount of nitric acid in accordance with the following equation:

It will be observed that, as a consequence of the above equation, 2 moles of nitric acid are required to dinitrate a single mole of 4-*t*-butylchlorobenzene. However, in the method of this invention, it has been found necessary to employ about twice this stoichiometric amount. On the other hand, it has not been found necessary to employ the concentrated sulfuric acid in a 2:1 molar ratio to the nitric acid, as set out in the above equation. Rather, the highest observed yields resulted from using a mixture of the two acids in approximately a 1.3:1 to 1.5:1 range of molar ratios (sulfuric to nitric).

While it is preferred to add the 4-*t*-butylchlorobenzene to a mixture of the nitric and sulfuric acids, it is also possible to dissolve the 4-*t*-butylchlorobenzene starting material in the sulfuric acid and then proceed to add this mixture to the nitric acid. In either

of these methods, it would be preferred to add the 4-*t*-butylchlorobenzene slowly to the nitric acid, rather than reversing the sequence by adding the nitric acid to the starting material. It is considered that the latter sequence would produce a significant amount of the unwanted mononitro-4-*t*-butylchlorobenzene.

Since both of the concentrated acids employed in the method of this invention contain a certain amount of water, the mixture of these acids used as the nitrating agent may be regarded as an aqueous solution. It is preferred to use the mixture of the acids alone, without additional solvents or media, and thus it may be seen that the nitration process of this invention, in its preferred form, takes place in an aqueous medium, essentially. However, it is possible to conduct the nitration process in an inert solvent medium. Useful solvents for

35 this purpose include chlorinated and unchlorinated aliphatic hydrocarbons containing from 5 to 10 carbon atoms, aromatic hydrocarbons, chloroform and carbon tetrachloride.

The addition of the 4-*t*-butylchlorobenzene starting material to the mixture of nitric and sulfuric acids, 40 when done on a laboratory scale, preferably takes place, dropwise, and with cooling of the reaction mixture. These precautions are simply a consequence of the exothermic nature of the nitration reaction. Since there is apparently no danger from potentially explosive reaction products, addition of the reactants may take place rapidly provided that steps are taken to assure cooling of the reaction mixture sufficient to prevent degradation of the final product. However, as the results obtained with the procedure followed in 45 Example 4 hereinafter indicate, where the temperature of the reaction mixture is permitted to rise quickly, by means of the exotherm being generated, to the temperature at which the reaction is to be conducted, a significant loss of yield appears to result. It is, therefore, 50 preferred to maintain the reaction mixture at an intermediate temperature in the range of 20°-40°C. until such time as the exotherm has subsided. The reaction mixture is then slowly brought to the higher temperature at which the reaction is completed.

60 As exemplified hereinbelow, in order to prevent overheating of the reaction mixture, the reaction was initiated with chilled reactants, and at below room temperature. While the exothermic reaction proceeded, cooling was effected sufficient to maintain the reaction mixture at a temperature of about 30°C.

After the exotherm has substantially subsided (simply measured by a drop in temperature), the reaction is carried to completion by slowly elevating the tempera-

ture of the reaction mixture to 100°C. or higher, and maintaining the reaction mixture at this temperature for a period of at least 1 hour, and preferably 2 hours. While temperatures in excess of 100°C. for conducting the reaction should be approached with caution, the results as set out in Table IV hereinbelow, obtained with such temperatures, specifically 115°C., indicate that yields obtained with the higher temperatures will be approximately the same as those obtained using 100°C.

When the reaction has been essentially completed, it has been found easiest to effect separation of the final product from the reaction mixture by utilizing phase separation, since the final product is solid at room temperature while the reaction remains liquid. This separation is thus simply accomplished by pouring the reaction mixture, after completion of the reaction, over cracked ice, and then proceeding to separate the solid final product from the reaction mixture by means of a Buchner funnel. Of course, it would also be possible to accomplish separation of the final product by means of solvent extraction. Suitable solvents are, for example, chlorinated and unchlorinated aliphatic hydrocarbons containing from 5 to 10 carbon atoms, aromatic hydrocarbons, ethers, chloroform and carbontetrachloride. This method was employed in Example 1 hereinbelow because of the gummy nature of the final reaction product, which contained a substantial proportion of mononitro-4-tert-butylchlorobenzene.

The final reaction product, once recovered, is washed with water and a basic material, such as sodium bicarbonate, to remove any traces of acid which may have carried over with it during the recovering process.

The nitration process of this invention is preferably carried out at atmospheric pressure, although the process may be carried out at either elevated or reduced pressures as well.

As shown in Table IV hereinbelow, the crude yields obtained by the nitration process of this invention are very nearly quantitative. Gas chromatographic analysis of this crude product gives the percent of crude product, which is 2,6-dinitro-4-tert-butylchlorobenzene.

The values under the column headed "Pure Dinitro (percent)", in Table IV, were derived by multiplication of the crude yield percentage and the percentage 2,6-dinitro calculated from gas chromatographic analysis.

5 The percentage mononitro-4-tert-butylchlorobenzene and percentage unknowns were also calculated from gas chromatographic analysis.

Using 4-tert-butylchlorobenzene as the starting material, the nitration process of this invention will produce

10 4-tert-butyl-2,6-dinitrochlorobenzene in excellent yields. In order to prepare the herbicidally active and plant growth regulant compounds of Formula I, it is necessary to react the chlorobenzene intermediate with a primary amine. Such an amine is generally liquid and 15 soluble in the organic solvents, such as toluene, xylene, alcohol, and the like, usually employed as the reaction medium. Where the amine is water soluble, there can be conveniently employed an aqueous medium, such as an alcohol-water solvent. The reaction is readily effected by adding a solution of the primary amine reactant, dropwise, to the chlorobenzene intermediate, both reactants being contained in the same solvent. 20 The amine is ordinarily employed in an excess amount on a molar basis. Upon completion of the addition, the 25 mixture is refluxed until the reaction is completed. The course of the reaction can be followed by the formation of the hydrochloride salt of the unreacted amine, which usually separates out as a solid precipitate. This precipitate is separated by filtering and the filtrate is evaporated to dryness. The solid residue obtained is recrystallized from an organic solvent, such as methanol, ethanol, or the like, to give a pure product.

The primary amine reactant is chosen on the basis of the mono-N-substituent which is desired in the resultant compound of Formula I. Thus, following the general procedure as described hereinabove and as will be more specifically shown in the examples which follow, 4-tert-butyl- and 4-sec-butyl-2,6-dinitrochlorobenzene was reacted with inter alia the amines shown in Table II 40 to give the corresponding compounds of Formula I as shown.

A. NITRATION

Example 1

16.9 g. (0.10 mole) of 4-tert-butylchlorobenzene was added, dropwise, over a period of 10-15 minutes to a mixture of 18.5 ml. of 90% by weight nitric acid (sp.gr. 1.49) and concentrated sulfuric acid (sp.gr. 1.84), with stirring and with a temperature of 15°-20°C. The reaction was slightly exothermic and after the addition was complete, the mixture was allowed to come to 30°C. and was maintained at that temperature until the reaction was complete, cooling when necessary. When the liberation of heat from the reaction had ceased, the temperature was raised slowly to 60°-65°C. and held at that level for 2 hours. The mixture was then cooled to room temperature and poured over cracked ice. The yellowish, semisolid reaction product was extracted with ether and this ether solution was then washed with portions of water, dilute sodium bicarbonate and again water. The ether solution was evaporated to dryness, leaving a residue of 18 g. of yellow, semisolid reaction product. The results of the nitration process just described are set out below in Table III.

Example 2

16.9 g. (0.10 mole) of 4-tert-butylchlorobenzene,

reaction was allowed to raise the temperature to 30°C. and completion of the reaction was noted by the subsequent drop in temperature. After the reaction was complete, the mixture was heated slowly to 70°-75°C. and maintained at that level for 1 hour. The mixture was then cooled to room temperature and poured over cracked ice. The resultant reaction product was collected on a Buchner funnel and, after drying, gave 22 g. of a dark yellow, somewhat gummy, solid with a melting point of 86°-98°C. Recrystallization from ethanol gave 20.5 g. of light yellow solid with a melting point of 109°-111°C. The results are summarized in Table III hereinbelow.

Example 3

16.9 g. (0.10 mole) of 4-tert-butylchlorobenzene was added, dropwise, over a period of 10-15 minutes to a mixture of 28 ml. of 90% by weight nitric acid (sp.gr. 1.49) and 84 g. of concentrated sulfuric acid (sp.gr. 1.84), with stirring and with the temperature at 15°-20°C. After complete addition, the temperature was allowed to come to 30°C. where it was maintained until completion of the reaction. The mixture was then heated slowly to 95°-100°C. and maintained at this level for 45 minutes. The reaction mixture was next cooled to room temperature, poured over cracked ice and collected on a Buchner funnel. The result was 23 g. of light yellow reaction product with a melting point of 91°-101°C. The results are summarized in Table III hereinbelow.

TABLE III

Example	4-tert-Butyl-Chlorobenzene	90% HNO ₃ (moles)	H ₂ SO ₄ (moles)	Final T°C	Wt. Crude	Yield Crude	% Mono	% Di	% Un-	Yield Pure Dinitro
1	.10 mol.	.40	.56	60-65	18g	69.5%	—	86.5	13.5	60.0%
2	.10 mol.	.60	.82	70-75	22g	85.5%	5.6	90.6	3.7	77.6%
3	.10 mol.	.60	.82	95-100	23g	89.0%	3.8	94.7	1.5	84.5%

which is liquid at room temperature, was added, dropwise, over a 10-15 minute period to a mixture of 28 ml. of 90% by weight nitric acid (sp.gr. 1.49) and 84 g. of concentrated sulfuric acid (sp.gr. 1.84), with stirring and with the temperature at 15°-20°C. The exothermic

65

Example 4

16.9 g. (0.10 mole) of 4-tert-butylchlorobenzene was added, dropwise, over a period of 10-15 minutes to a mixture of 28 ml. of 90% nitric acid (sp.gr. 1.49) and 84 g. of concentrated sulfuric acid (sp.gr. 1.84), with

stirring and with the temperature at 15°–20°C. The exotherm which occurred as a result of the addition was permitted to raise the temperature of the reaction mixture to about 100°C. This required approximately 5 minutes. The reaction mixture was maintained at this temperature by the addition of heat for another 1 hour and 45 minutes. The reaction mixture was next cooled to room temperature, poured over cracked ice and collected on a Buchner funnel. The result was 23.3 g. of light yellow reaction product.

The reaction process, specifically described in the examples above, was repeated with varying proportions of nitric and sulfuric acids, different reaction times, and under different temperature conditions. The results are summarized in Table IV hereinbelow.

*2,6-dinitro-t-butylchlorobenzene

**2-nitro-t-butylchlorobenzene

***Red fuming sp.gr. 1.60

**** This run followed the procedure detailed in Example 4

The 4-tert-butyl-2,6-dinitrochlorobenzene, which is the reaction product of the nitration process described in detail hereinabove, is, in turn, reacted with a primary amine to give the 4-tert-butyl-mono-N-substituted-2,6-dinitroanilines of Formula I. This amination process is specifically described in the examples which follow:

B. AMINATION

Example 5

1 g. of 4-tert-butyl-2,6-dinitrochlorobenzene was allowed to react with 1 g. of sec-butylamine by adding the amine, dropwise, to a refluxing mixture of 50 ml. dry toluene and the 4-tert-butyl-2,6-dinitrochlorobenzene. After complete addition, the refluxing was continued for 8 hours. The mixture was then cooled to room temperature, the hydrochloride salt of the amine filtered off, and the toluene and unreacted amine removed under reduced pressure. The thick material that resulted was dissolved in hot ethanol. The reaction product, which was then crystallized by cooling, was 4-tert-butyl-N-sec-butyl-2,6-dinitroaniline with a melting point of 60°–72°C.

Example 6

2.6 g. (0.10 mole) of 4-tert-butyl-2,6-dinitrochlorobenzene was reacted with 3.1 g. of a 40% aqueous

solution of methylamine in 50 ml. of ethanol. The temperature was slowly increased as follows: 30°C. for 1 hour, 40°C. for 1 hour, 50°C. for 1 hour, then 80°C. for 5 hours. When the reaction was complete, about 100 ml. of water was added, which precipitated the reaction product. This product was filtered, washed with portions of water, and upon recrystallization from ethanol yielded 2.5 g. of 4-tert-butyl-N-methyl-2,6-dinitroaniline as orange needles melting at 129°–130°C.

10 By using a method similar to those described in the preceding examples, additional 4-tert-butyl-N-mono-substituted-2,6-dinitroanilines derivatives were prepared by reacting 4-tert-butyl-2,6-dinitrochlorobenzene with the appropriate primary amine. These compounds, together with those mentioned in the preced-

ing examples, are listed in Table II hereinabove.

I claim:

45 1. A process for preparing 4-R-2,6-dinitrochlorobenzene compounds of the formula:

55 wherein R is selected from the group consisting of branched chain hydrocarbons containing from 3 to 7 carbon atoms, comprising the step of treating a compound of the formula:

60 65 with a mixture of concentrated sulfuric acid of at least 98% concentration by weight and concentrated nitric acid of greater than 70 percent concentration by

13

weight at a temperature of from about 15°C to about 115°C for at least 1 hour, whereby the reaction is carried to substantial completion.

2. The process of claim 1, wherein the temperature is maintained at about 20°C to about 40°C until an exotherm, which is produced by the reaction, has substantially subsided; then slowly raising the temperature to about 60°C to about 115°C, and maintaining the temperature for a sufficient period of time to allow the reaction to be carried to substantial completion.

3. The process of claim 1, wherein the concentration of the nitric acid is at least 90 percent by weight.

4. The process of claim 1, wherein the step of treating in a mixture of concentrated sulfuric and nitric acids is

conducted at a temperature of about 100°C. for a period of about 2 hours.

5. The process of claim 1, wherein the concentrated sulfuric acid is fuming sulfuric acid.

6. The process of claim 1, wherein R is tert-butyl.

7. The process of claim 2, wherein the concentrated sulfuric acid is fuming sulfuric acid.

8. The process of claim 2, wherein the concentrated nitric acid is at least 90 percent concentration.

9. The process of claim 8, wherein the concentrated nitric acid is about 98 percent concentration.

10. The process of claim 2, in the step of slowly raising the temperature, the temperature is raised to about 60° to 65°C.
